Application April 22, 1950, Serial No. 157,586

Claims priority, application Sweden May 5, 1949

9 Claims. (Cl. 62—119.5)

1

My invention relates to refrigeration, and more particularly to a refrigeration system employing evaporation of refrigerant fluid in the presence of inert gas which is circulated by a force produced or developed within the system. Such motivating force for causing circulation of inert gas is produced by the difference in specific weight of columns of inert gas rich and weak in refrigerant, respectively, in the inert gas circuit.

It is an object of the invention to improve the operation of systems of this type having low and higher temperature evaporator sections or cooling elements, particularly to effect an extremely low temperature in the low temperature evaporator section.

Another object of the invention is to provide an improvement in such a system having low and higher temperature evaporator sections in which the circulation of inert gas is better correlated to the temperature level at which the low temperature evaporator section operates.

A further object is to provide an improvement in such a system having a low temperature evaporator section suitable for freezing purposes in which the force developed within the system for causing circulation of inert gas through the low temperature evaporator section is more nearly related to the specific weight of the inert gas in such evaporator section rather than to the specific weight of inert gas in other parts of the system having a higher partial pressure of refrigerant.

A still further object is to provide an improvement in such a system having low and higher temperature evaporator sections by correlating the circulation of inert gas through the low temperature section to the temperature level at which evaporation of refrigerant is effected therein, and by subdividing the inert gas into a plurality of streams in parallel relation not only in the low temperature evaporator section but desirably also in the absorber to insure such gas circulation at a reduced flow rate through the low temperature evaporator section.

The invention, together with the above and further objects and advantages thereof, will be more fully understood upon reference to the following description and accompanying drawing forming a part of this specification, and of which the single figure illustrates more or less diagrammatically a refrigeration system embodying the invention.

Referring to the drawing, I have shown my invention in connection with an absorption re-

frigeration system of a uniform pressure type which is well known in the art and in which an inert pressure equalizing gas is employed. Such a refrigeration system comprises a generator or boiler 10 containing a refrigerant, such as ammonia, in solution in a body of absorption liquid, such as water. Heat is supplied to the boiler 10 from a heating tube or flue 11 thermally connected therewith at 12, as by welding, for example. The heating tube 11 may be heated in any suitable manner, as by an electrical heating element disposed within the lower part of the heating tube or by a liquid or gaseous fuel burner 14 which is adapted to project its flame into the lower end of the tube.

The heat supplied to the boiler 10 and its contents expels refrigerant vapor out of solution, and such vapor passes upwardly through a conduit 15 and air cooled rectifier 16 into an air cooled condenser 17 in which it is condensed and liquefied. Liquid refrigerant flows from condenser 17 through a conduit 18, vessel 19 and conduit 20 into a first evaporator section 21. As will be explained more fully hereinafter, liquid refrigerant in the evaporator section 21 evaporates and diffuses into an inert pressure equalizing gas, such as hydrogen, which enters through a conduit 22. Due to evaporation of refrigerant into inert gas, a refrigerating effect is produced with consequent absorption of heat from the surroundings.

Inert gas enriched in refrigerant vapor and formed in evaporator section 21 flows therefrom through a conduit 23 and one passage 24 of a gas heat exchanger 25 to an absorber 26 having an absorber vessel 27 at the lower part thereof. As will be explained more fully hereinafter, the gas mixture in absorber 26 flows counter-current to downwardly flowing absorption liquid which enters through a conduit 28. The absorption liquid absorbs refrigerant vapor from inert gas, and inert gas weak in refrigerant vapor flows from absorber 26 in a path of flow including a passage 29 of gas heat exchanger 25 and conduit 22 into evaporator section 21.

Absorption solution enriched in refrigerant flows from the absorber 26 into absorber vessel 27 and from the latter through a conduit 30 and an inner passage or pipe 31 of a liquid heat exchanger 32 into the lower end of a vapor lift tube or pipe 33. Liquid is raised by vapor-liquid lift action through pipe 33, which is in thermal relation with the heating tube 11 at 34, into the upper part of the boiler 10. Refrigerant vapor expelled out of solution in boiler 10, together

with refrigerant vapor entering through pipe 33, flows upwardly through conduit 15 to the condenser 17, as previously explained. The absorption liquid from which refrigerant vapor has been expelled flows from the boiler 10 through a connection 35, outer passage 36 of liquid heat exchanger 32 and conduit 37 whose upper end is in communication with the conduit 28, as will be explained presently. The circulation of absorption solution in the liquid circuit just described is effected by raising of liquid through pipe 33.

The outlet end of condenser 17 is connected by conduit 58, vessel 59 and conduit 60 to a part of the gas circuit, as at 61, for example, so that any inert gas which may pass through the condenser can flow into the gas circuit. Refrigerant vapor not liquefied in the condenser 17 flows through conduit 58 to displace inert gas in vessel 59 and force such gas into the gas circuit. The effect of forcing gas into the gas circuit in this manner is to raise the total pressure in the entire system whereby an adequate condensing pressure is obtained to insure condensation of refrigerant vapor in condenser 17.

In order to effect a low refrigerating temperature in evaporator section 21 the vessel 19 is arranged to operate as a precooler for reducing the temperature of liquid refrigerant supplied to evaporator section 21. In vessel 19 liquid refrigerant conducted therethrough is precooled by evaporation of refrigerant into inert gas partially enriched in refrigerant and flowing thereto through a conduit 38 which is connected to an upper part of evaporator section 21. Liquid refrigerant in vessel 19, which may be referred to as a second evaporator section, evaporates and diffuses into partially enriched gas, thereby taking up heat from the liquid refrigerant. Liquid refrigerant precooled in this manner passes to the upper part of evaporator section 21 through conduit 20 which is formed to provide a liquid trap.

A third evaporator section 39 provided with heat transfer fins 40 is connected to receive inert gas and liquid refrigerant from a lower part of evaporator section 21. Inert gas enriched in refrigerant flows from evaporator section 39 through a conduit 41 to which is also connected a conduit 42 whose upper end is connected to vessel 19. Hence, enriched inert gas flows from both the precooler vessel or second evaporator section 19 and the third evaporator section 39 through conduit 41 to an outer passage 43 of a second gas heat exchanger 44 and thence through a conduit 45 to the absorber vessel 27.

The circulation of inert gas in refrigeration systems of the type under consideration is due to the difference in specific weight of the columns of gas enriched and weak, respectively, in refrigerant vapor. Since a column of gas enriched in refrigerant vapor and flowing from an evaporator to the absorber is heavier than a column of gas weak in refrigerant vapor and flowing from the absorber to the evaporator, a force is produced or developed within the system for causing circulation of gas.

In refrigeration systems of the inert gas type it is usually the practice to provide several evaporator sections, one of which serves as a freezing section adapted to operate below the freezing temperature of water and another of which is employed for general food preservation and is adapted to operate above such freezing temperature. The low and higher temperature evaporator sec-

tions are usually connected in series and the inert gas flows successively through the freezing and higher temperature evaporator sections, so that the gas in the higher temperature sections contains a greater amount of refrigerant vapor than the gas in the freezing section. Since the driving force developed for causing circulation of inert gas is dependent upon the increase in specific weight or density of inert gas due to evaporation of refrigerant in both evaporator sections, the driving force for effecting gas circulation generally is determined by inert gas having the highest partial pressure of refrigerant and therefore the highest evaporating temperature of refrigerant in the system.

It is already known that the circulation of inert gas should not be greater than necessary to take care of the quantity of refrigerant that evaporates to satisfy and meet the load or refrigerating requirement. When the circulation of gas is greater than necessary, the efficiency of the gas heat exchanger is reduced and so-called "gas losses" result due to the fact that a greater quantity of weak inert gas from the relatively high temperature absorber is introduced into the freezing evaporator section than is actually required. Hence, while this problem has been recognized and provision has been made to effect a reduction in circulation of inert gas under certain operating conditions, such reduction in gas circulation has been effected in both the freezing and higher temperature evaporator sections and is dependent upon flow of unevaporated refrigerant from both the low and higher temperature evaporator sections.

In accordance with my invention the inert gas circuit including the low temperature evaporator section 21 and absorber 26 is formed and arranged so that the circulation of inert gas through such low temperature evaporator section is correlated more effectively to the freezing temperatures produced by this evaporator section and not dependent to any substantial extent upon inert gas having the highest partial pressure of refrigerant in the system. In the preferred embodiment of the invention illustrated, this is accomplished by providing in the low temperature evaporator section 21 and also in the absorber 26 a number of paths of flow for inert gas which are connected in parallel.

The low temperature evaporator section 21 comprises a pair of spaced apart headers 46 and 47 between which are connected a number of inclined conduits 48 disposed at different levels. The conduits 48 are in open communication with the headers 46 and 47, the lower ends of the top and intermediate conduits being formed with liquid barriers 49 to divert liquid into conduits 50 whose lower ends are connected to the higher located end of the next lower conduit 48. Hence, liquid will flow from vessel 19 into the top conduit 48 through the conduit 20. From the lower end of the top conduit 48 liquid passes through the first connection 50 into the upper end of the intermediate conduit 48, and from the lower end of the latter through the second connection 50 into the bottom conduit 48. The bottom conduit 48 may also be provided with a liquid barrier 49 from which liquid will pass into the bottom of header 48 and then flow by gravity through the evaporator section 39.

The conduits 48 may be provided with internal screening, or the inner surfaces may be otherwise formed to effect distribution of liquid refrigerant by capillary action, for example, so

that an extensive gas and liquid contact surface will be obtained. Inert gas weak in refrigerant flows from conduit 22 into header 46 where the gas is subdivided into a plurality of streams for flow through the several conduits 48. The streams of gas merge in header 47 and flow through conduit 23 to the absorber 26, as previously explained.

The absorber 26 also comprises a pair of spaced apart headers 51 and 52 between which are connected a number of inclined conduits 53. The lower ends of conduits 53 are formed with liquid barriers 54 and liquid is conducted from the lower ends of the top and intermediate conduits 53 through connections 55 to the next lower conduit. It will now be apparent that absorption liquid entering the top conduit 53 through conduit 28 flows downwardly through each conduit 53 and passes from the lower end of bottom conduit 53 into the absorber vessel 27. Inert gas enriched in refrigerant flows from conduit 23 through the passage 24 of gas heat exchanger 25 into the absorber header 51. The inert gas is then subdivided into several streams for flow through the conduits 53 in which refrigerant vapor is absorbed into solution. Inert gas weak in refrigerant flows upwardly through header 52 whose upper end is in communication with the passage 29 of the gas heat exchanger.

Since inert gas weak in refrigerant and flowing from absorber 26 is initially introduced into the first evaporator section 21, and precooled liquid refrigerant evaporates and diffuses into such weak gas with consequent absorption of heat from the surroundings, a low temperature refrigerating effect is produced which is suitable for freezing purposes. By reason of the low temperature at which the first evaporator section 21 operates, the partial vapor pressure of refrigerant in the inert gas emerging from header 47 and flowing to the absorber 26 is comparatively low. Due to absorption of refrigerant into absorption solution in the absorber 26, inert gas weak in refrigerant flows upwardly in absorber header 52 and flows through an inner passage 56 of the second gas heat exchanger 44.

Absorption liquid weak in refrigerant and flowing from boiler 10 is initially introduced into the presence of inert gas in the inner passage 56 of the gas heat exchanger 44. The lower end of passage 56 is formed with a barrier or dam 57 for diverting absorption liquid into conduit 28 for flow through successive conduits 53 of the absorber 26. It will therefore be evident that the weak absorption liquid flowing from the boiler 10 is not only cooled in the liquid heat exchanger 36 but also cooled further by flowing in heat exchange relation with relatively cool gas in the gas heat exchanger 44, such cool gas flowing to the outer passage 43 of the latter from the second and third evaporator sections 19 and 39, respectively.

Since the part of the absorber at which the weak absorption liquid is introduced and the weak inert gas passes or emerges therefrom tends to operate at a higher temperature than the rest of the absorber, it is advantageous to shift such part from the absorber 26 proper to the second gas heat exchanger 44. In this manner the intense cooling effect of the cool enriched inert gas in the outer passage 43 of heat exchanger 44 effectively takes up heat from both the weak absorption liquid and weak inert gas, and, as a result of such increased cooling, the inert gas passing out of contact with absorption liquid and flowing to the

first evaporator section 21 will be deprived of as much refrigerant as possible.

Inert gas enriched in refrigerant flows from the outer passage 43 of gas heat exchanger 44 through conduit 45 into the end of absorber vessel 27 opposite to that at which the header 51 is connected to the absorber vessel. Since the gas mixture flowing through conduit 45 is gas which is enriched in refrigerant in the vessel 19 and second evaporator 39, such gas has the highest partial pressure of refrigerant in the system. However, such rich gas passes through the absorber vessel 27 before entering the lower end of the header 51, and in passing in intimate contact with absorption liquid in the vessel 27 the liquid absorbs refrigerant vapor from the inert gas. Hence, the absorber vessel 27 serves as an active part of the absorber unit of the system, and the partial vapor pressure of refrigerant in the inert gas passing through the vessel is reduced by the time it enters the lower end of absorber header 51 and mixes with inert gas flowing thereto from the low temperature evaporator section 21. While absorption of refrigerant into solution may take place at a relatively high temperature in the absorber vessel 27, such absorption of refrigerant is realized because of the comparatively high partial pressure of refrigerant vapor in the gas mixture.

It will now be understood that the circulation of inert gas between the low temperature evaporator section 21 and absorber 26 is primarily due to the difference in specific weight of the column of weak gas flowing from the absorber 26 to evaporator section 21 and the column of enriched gas flowing from evaporator section 21 to the absorber 26. Accordingly, the force developed within the system for causing circulation of inert gas through the low temperature evaporator section 21 will be more nearly related to and better correlated with the specific weight of the gas mixture produced in the low temperature evaporator section rather than to the higher specific weight of the inert gas flowing from the other evaporator sections through conduit 45 into the absorber vessel 27. Even though there sometimes may be a tendency for the gas mixture from absorber vessel 27 to remain segregated in header 51 from the gas mixture of less specific weight entering the upper part of such absorber header, and the heavier gas mixture may tend to flow through the lower located conduits 53 and the lighter gas mixture through the higher located conduits, nevertheless the gas circulation will be better correlated to the temperature level at which the low temperature evaporator section 21 operates. This is so because the driving force developed in the gas circuit by the evaporation of refrigerant in the evaporator section 21 is less than the sum total of the driving forces developed in all of the places of evaporation in the system.

The fact that the inert gas is subdivided into a plurality of parallel streams in the evaporator section 21 and absorber 26 contributes immeasurably to the production of the desired refrigerating effect in such evaporator section at the low temperatures produced therein. As a matter of fact, the provision of parallel paths of flow for inert gas in the low temperature evaporator section 21 and absorber 26 makes it possible to provide a commercially practicable refrigeration system capable of producing refrigerating temperatures of -5° C. and lower. With such an arrangement the resistance offered to flow of

inert gas is reduced to such an extent that adequate gas circulation is assured under all operating conditions encountered in practice even though the driving or motivating force to cause such gas circulation is not of the highest magnitude capable of being developed in the system, as is the case when advantage is taken of inert gas having the highest partial pressure of refrigerant vapor which is produced in one or more higher temperature evaporator sections.

While I have shown and described a single embodiment of my invention, it will be apparent to those skilled in the art that modifications and changes may be made without departing from the spirit and scope of the invention. I therefore do not wish to be limited to the embodiment shown in the drawing and described in the specification, and I intend in the following claims to cover all modifications and changes which fall within the true spirit and scope of the invention.

What is claimed is:

1. In absorption refrigeration apparatus, a circuit for circulation of inert gas including evaporating means in which liquid refrigerant evaporates in the presence of inert gas to produce a refrigerating effect and absorbing means in which refrigerant vapor is absorbed from inert gas into absorption liquid, at least one of said means comprising a pair of spaced apart vertically extending end headers, a number of horizontally extending conduits at different levels, each of said conduits having one end connected to one end header and the opposite end connected to the other end header, means for conducting liquid for said one means to the uppermost conduit, and connections for conducting liquid through successively lower conduits for gravity flow therein, the circulation of inert gas through said conduits in a number of parallel flow paths from one header to the other header being effected solely due to the varying partial pressure of refrigerant vapor in different parts of the inert gas circuit.

2. In absorption refrigeration apparatus, a circuit for circulation of inert gas including evaporating means in which liquid refrigerant evaporates in the presence of inert gas to produce a refrigerating effect and absorbing means in which refrigerant vapor is absorbed from inert gas into absorption liquid, at least one of said means comprising a pair of spaced apart vertically extending end headers, a number of horizontally extending conduits at different levels, each of said conduits having one end connected to one end header and the opposite end connected to the other end header, means for conducting liquid for said one means to the uppermost conduit for gravity flow therein, and a connection including a liquid trap for conducting liquid from each conduit to the next lower conduit for gravity flow therein, the circulation of gas through said conduits in a number of parallel flow paths from one end header to the other end header being effected solely due to the varying partial pressure of refrigerant vapor in different parts of the inert gas circuit.

3. In absorption refrigeration apparatus, low and higher temperature places of evaporation in which liquid refrigerant evaporates in the presence of an inert gas to produce a refrigerating effect, first and second places of absorption in which refrigerant vapor is absorbed from inert gas into absorption liquid, connections to provide a primary circuit for circulation of inert gas which includes said low temperature place

of evaporation and first place of absorption, such circulation of inert gas being produced by a driving force developed within the apparatus which is primarily dependent upon the difference in specific weight of weak inert gas and enriched inert gas respectively flowing into and from said low temperature place of evaporation, at least one of the places of evaporation and absorption in said primary gas circuit comprising structure providing several paths for flowing inert gas therethrough in parallel, and additional connections to provide another circuit for circulation of inert gas through said higher temperature place of evaporation which includes separate conduit means for conducting enriched inert gas from the latter to said second place of absorption, said first place of absorption being connected to receive inert gas from the second place of absorption only after refrigerant vapor initially is absorbed from inert gas into absorption liquid in the latter.

4. In absorption refrigeration apparatus, low and higher temperature places of evaporation in which liquid refrigerant evaporates in the presence of an inert gas to produce a refrigerating effect, first and second places of absorption in which refrigerant vapor is absorbed from inert gas into absorption liquid, connections to provide a primary circuit for circulation of inert gas which includes said low temperature place of evaporation and first place of absorption, such circulation of inert gas being produced by a driving force developed within the apparatus which is primarily dependent upon the difference in specific weight of weak inert gas and enriched inert gas respectively flowing into and from said low temperature place of evaporation, at least one of the places of evaporation and absorption in said primary gas circuit comprising structure providing several paths for flowing inert gas therethrough in parallel, said higher temperature place of evaporation being connected to receive at least partially enriched inert gas from said low temperature place of evaporation, and separate conduit means for conducting enriched inert gas from the higher temperature place of evaporation to said second place of absorption, said first place of absorption being connected to receive inert gas from the second place of absorption only after refrigerant vapor initially is absorbed from inert gas into absorption liquid in the latter.

5. Apparatus as set forth in claim 4 including means for conducting liquid refrigerant to said higher temperature place of evaporation and from the latter to said low temperature place of evaporation.

6. In absorption refrigeration apparatus, low and higher temperature places of evaporation in which liquid refrigerant evaporates in the presence of an inert gas to produce a refrigerating effect, first and second places of absorption in which refrigerant vapor is absorbed from inert gas into absorption liquid, connections to provide a primary circuit for circulation of inert gas which includes said low temperature place of evaporation and first place of absorption, such circulation of inert gas being produced by a driving force developed within the apparatus which is dependent upon the difference in specific weight of weak inert gas and enriched inert gas respectively flowing into and from said low temperature place of evaporation, said connections including first conduit means for conducting weak inert gas from said first place of absorption to said low temperature place of

evaporation and second conduit means for conducting enriched inert gas from the latter to said first place of absorption, and additional connections to provide another circuit for circulation of inert gas through said higher temperature place of evaporation which includes third conduit means for conducting enriched inert gas from the latter to said second place of absorption, said first place of absorption being connected to receive inert gas from the second place of absorption only after refrigerant vapor initially is absorbed from inert gas into absorption liquid in the latter, and said first, second and third conduit means being formed and arranged so that weak inert gas from the first place of absorption flows in heat exchange relation consecutively with enriched inert gas from one place of evaporation and thereafter with enriched inert gas from another place of evaporation.

7. Apparatus as set forth in claim 6 including means for conducting absorption solution in heat exchange relation with weak inert gas issuing from said first place of absorption and thereafter to said first place of absorption.

8. Apparatus as set forth in claim 6 in which said first, second and third conduit means are formed and arranged so that weak inert gas from the first place of absorption flows in heat exchange relation consecutively with enriched inert gas from said higher temperature place of evaporation and thereafter with enriched inert

gas from said low temperature place of evaporation, and means for conducting absorption solution in heat exchange relation with weak inert gas in the part of said first conduit means in heat exchange with said third conduit means and thereafter to said first place of absorption.

9. Apparatus as set forth in claim 8 in which said means for conducting absorption solution is constructed and arranged to bring the solution in intimate contact with weak inert gas in said first conduit means.
